OSCILLATING FAN

Nestor J. Guardado, Buenos Aires, Argentina
 Application June 11, 1951, Serial No. 231,033
 3 Claims. (Cl. 230—257)

The object of the present invention is an oscillating fan characterized by the fact that the assembly formed by the motor and blades is mounted within a suspension system capable of freely swinging in three directions, i. e., a gimbal-type suspension.

The three orthogonal axes coincide at a fixed point in space, said point being, at the same time, the barycenter of the system.

The fan body is provided with a trunnion projecting therefrom and contacting a guide fixed to the foot of the fan. Said guide, at its side confronting the trunnion, possesses a spherical cap shaped recess, the center of which coincides with the barycenter of the system.

The contour of this recess may be a closed figure, such as an oval or any other figure over which said trunnion may travel.

Bearing in mind that the fan constitutes a rapidly rotating mass, its behavior is that of a gyroscope and, therefore, taking advantage of the gyroscope's well known tendency to place its axis in parallel relation to the attracting moment, it is possible to apply to same an alternative couple that causes the fan to oscillate.

This particularity offers two well-defined possibilities, which are:

(1) A compound oscillatory motion, i. e., the fan axis can be made to describe a combined oscillatory movement, swinging in a horizontal as well as in a vertical plane.

(2) Inasmuch as the system chosen has no direct mechanical connection with the motor, same is especially indicated in the case of fans, particularly small ones which, precisely due to their reduced size, are low-powered and whose efficiency (volume of air set in motion) is remarkably reduced through the usual methods of gear reductions, etc. With the present system, the only energy consumed is that required to overcome the friction present in the moving parts. From the practical point of view, the energy employed in motion is negligible.

The following advantages are thus obtainable:

- (a) Greater area swept by the air cone.
- (b) Simple mechanical execution, devoid of wear.
- (c) Reduced cost as compared with the classic methods applicable to cheap, low-powered types of fans.

The invention likewise envisages other accessory objects, as will be made clear in the course of the present specification.

In order that the present invention may be easily understood and readily put into practice, a preferred embodiment thereof will now be explained with particular reference to attached drawings.

In the drawings:

Figure 1 illustrates an endwise view partially in section, showing the mounting of the gimbal suspension and the arrangement of the guide enabling displacement of same in a compound oscillatory movement.

Figure 2 is a rear view of the fan.

2

Figure 3 is a plan view showing the particular shape of the guide recess.

Figure 4 is an end view of a fan equipped with a specially shaped guide permitting oscillatory motion in a substantially horizontal plane.

Figure 5 is a plan view of the fan illustrated in Figure 4.

Like numerals represent like or similar parts throughout the several figures of the drawings.

As can be seen from the illustrations, fan 1 is mounted in a universal or gimbal suspension, i. e., a system having freedom of movement in three directions: one according to the motor's own rotation and two further rotations in normal planes. The three orthogonal axes of rotation xx' , yy' and zz' pass through a point that is fixed in space and which coincides with the barycenter of the system.

It is well known that if a couple of forces is applied in a plane Z , X , see Figure 1, a movement called precession is obtained on axis Z , said movement being one of rotation. If M be the couple applied and I the moment of inertia of the rotor mass and ω the angular speed of rotation of the fan, a rotation Ω will then appear, as given by:

$$\Omega = \frac{M}{I\omega}$$

as per axis ZZ' .

Nutation has been disregarded inasmuch as in practice the value of the impulse proper of the fan greatly reduces such nutation.

$$(\text{precession}) \psi = \frac{M \cdot t}{I\omega} - \frac{M \cdot J}{I\omega} \cdot \sin \frac{I\omega t}{J}$$

The greater the impulse $(I\omega)$, the more negligible becomes the second—the oscillatory—term.

If it be required that the movement be a simple swinging motion, the guide can be made merely as a circular sector 2, Figure 4, having the centre of its curvature in the axis (ZZ') y and an aperture α , Figure 5, equal to the angle of rotation desired. The sides of the guide are surfaces of a truncated cone the vortex of the generatrices of which is the centre of rotation of the system. Guide 2 forms integral part of the standard or base 3 of the fan. It is provided, furthermore, with a control arm or trunnion 4 forming integral part of the fan 1 and resting on guide 2, the direction of which is that of a generatrix. The presence of a couple of forces in the plane ZX , an unexpected phenomenon when considering the principle of the tenacity of the gyroscope axes, is explained by the fact that, inasmuch as there is no perfect dynamic equilibrium within trunnion 4 resting on guide 2, a vibratory movement is produced, the frequency of which is equal to the rotation of the machine that, as it rests on the guide, originates in the trunnion a force equal and contrary to the oscillatory force applied against the wall and corresponding to the supporting vibratory semicircles, to which must be added the couple caused by the change in direction of the impulse vector. The magnitude of the couple introduced by the arrangement according to the invention, depends on (1) the dynamic unbalance caused by the system; (2) the impulse proper of the machine's rotation; (3) the distance of the momentary centre of rotation to the supporting point; (4) the resiliency of the supporting trunnion; and (5) the materials chosen for the contact between guide and trunnion and the friction of the contact surfaces in question.

By an adequate combination of all these factors, it is possible, in each case, to obtain an oscillation period of pre-established frequency.

Looking at the fan from behind, and considering that same is then turning in a clockwise direction, if the

trunnion rests on the outer portion of the guide (placed on the observer's side), the precessional rotation will take place over axis ZZ' and, seen from above, the consequent rotation will also be clockwise.

Once the end of the guide has been reached, and owing to the fact that the motion occurs in a vertical plane, the direction in which the trunnion is supported is reversed and the fan will now turn in a counterclockwise manner. The guide, instead of a projection, can be a recess in which the supporting action on the front and rear flanks reverses the rotation. Guide 2, furthermore, is designed in such a manner as to cause the swinging motion to take place according to several degrees of inclination. To that end, a series of concentrical channels is provided (5), see Figure 5, following the curvature (sinus) of the angle (Figure 4). Similarly, if we place the guide in a vertical plane passing through the momentary centre of rotation, a vertical oscillatory motion is obtained.

The moment, now, is applied along axis ZZ' and in agreement with the above described principle. The precessional movement thus takes place along axis YY' and an oscillatory motion in a vertical plane is then brought about in the above explained fashion.

A combination of both arrangements produces a combined motion, i. e., trunnion 4 will follow any guide 2 presenting a recess or a projection 6, Figure 3, representing a closed figure and situated on a spherical cap the centre of which coincides with the centre of rotation of the gimbal system and with the barycenter of the system.

The invention as described may be clearly understood and further explanations will not be required by those versed in the art.

It is evident that diverse changes can be made in the construction and details of the invention without thereby departing from the sphere of the present invention, the scope of which is clearly defined in the following claims.

I claim:

1. An oscillating fan comprising, in combination, fan blades dynamically unbalanced and operable about an axis, a motor for driving said fan blades, and comprising a housing and a rotor operatively connected to said fan blades, a fan mounting element having said motor housing pivotally mounted therein, a base member, said mounting element being pivotally mounted in said base member, said fan blades, axis, motor housing, and mounting element having intersecting orthogonal axes, said fan blades and motor constituting a unit having its center of gravity at the intersection of said orthogonal axes, a

projection on said base, one surface of said projection being the segment of a hollow sphere having its center coinciding with said intersection, closed guide means on said surface of said projection, and a control member on said motor housing in movable engagement with said guide means, said control member being fixed with respect to said fan blade axis and said motor housing, whereby, upon rotation of said fan blades, said control member is caused to nutate and engage one edge of said guide means, thus causing the fan to gyrate in a path determined by the configuration of said guide means.

2. An oscillating fan according to claim 1 wherein said projection has a series of closed concentric channels for selectively receiving said control member.

3. An oscillating fan comprising, in combination, a fan unit having fan blade elements rotatable about a first axis, the dynamic equilibrium of said elements and said unit being imperfect, a motor for driving said fan unit, said motor being operatively connected to said fan blade elements, a support, said fan unit being pivotally mounted on said support for pivoting about a second axis perpendicular to the said first axis of rotation of the blade elements, a base, a projection on said base and having one surface in the form of the segment of a hollow sphere, said support being pivotally mounted on said base for pivoting about a third axis perpendicular to the two aforesaid axes, said three orthogonal axes intersecting at a common point, said unit having its barycenter at the intersection of said orthogonal axes, closed guide means on said segment of said hollow sphere, said sphere having its center coincident with said intersection, and a control member on said motor in movable engagement with said guide means, said control member being fixed with respect to said motor and said fan unit, whereby, when the fan is rotating, the imperfection in the dynamic equilibrium of said elements and of said unit will impart to said control member relatively high frequency nutations which cause it to progressively engage one edge of the guide means to advance the unit in a path determined by the configuration of said guide means.
